(57) **CLAIM**

The ornamental design for the modular water jug rack unit, as shown and described.

DESCRIPTION

FIG. 1 is a perspective view showing the front, right and top sides of the modular water jug rack unit design.

FIG. 2 is a front view of the modular water jug rack unit design, the rear viewing being identical thereto.

FIG. 3 is a right side view of the modular water jug rack unit design, the left side being identical thereto.

FIG. 4 is a top view of the modular water jug rack unit design.

FIG. 5 is a bottom view of the modular water jug rack unit design; and,

FIG. 6 is a perspective view showing the front, right, and bottom sides of the modular water jug rack unit design.

1 Claim, 4 Drawing Sheets(56)
